UNITED STATES PATENT OFFICE.

BERTRAM M. MILLS, OF PAWTUCKET, RHODE ISLAND.

HUMIDIFIER.

Application filed June 9, 1921. Serial No. 476,220.

To all whom it may concern:

Be it known that I, BERTRAM M. MILLS, a citizen of the United States of America, and resident of Pawtucket, in the county of Providence and State of Rhode Island, have invented new and useful Improvements in Humidifiers, of which the following is a specification.

This invention concerns apparatus for moistening or humidifying air and relates more particularly to that type of apparatus wherein water from a suitable source of supply is mechanically atomized and discharged directly into the room or chamber where air is to be moistened.

When atmospheric air is artificially heated, as is usual in modern houses and manufacturing establishments, its humidity is very appreciably decreased. The deleterious effects of such unnaturally dry air upon the health of persons continually subjected thereto has long been recognized, as well as the fact that such desiccated air is injurious to wooden furniture and other objects of household utility. It is also a matter of common knowledge that such air interferes in a very serious way with the successful carrying out of certain manufacturing processes, notably such as are employed in the textile industry.

While efforts heretofore have been made to devise methods or means for furnishing the desired degree of moisture in artificially heated rooms or apartments, such efforts have been directed in large measure to the provision of mechanically operated apparatus suitable for use in textile mills or other manufacturing establishments where relatively large quantities of air must be treated. Such apparatus is commonly of large size, costly to install, unsightly in appearance and intended to occupy a fixed position. The relatively few attempts which have been made toward providing for the moistening of the air in dwelling houses have been confined almost wholly to the provision of moisture evaporative means applicable directly to the heating units employed, or to permanent installations of complicated character forming coordinate parts of the heating system. In view of the relative inefficiency of the latter forms of device and of the unsuitable character of the more efficient forms, such as have been employed in mills,

the use of air moistening devices, in so far as their application to dwelling houses is concerned, is very infrequent, although it is highly desirable, from the standpoint of health, that the air in such places be properly moistened.

The principal object of the present invention is to provide air moistening means suitable for use in dwelling houses and more particularly to furnish means of a portable character and such as may readily be moved from place to place or from room to room in an apartment or dwelling house, and which at the same time shall be unobjectionable in appearance and entirely independent of the heating system employed.

A further object of the invention is to provide simple and effective means, whether embodied in apparatus of portable character or not, whereby liquid may be atomized by mechanical means and in practical quantities without any appreciable discharge of droplets of moisture, and whereby the atomized liquid thus produced may be distributed in an efficient manner into the surrounding atmosphere, and in accordance with certain forms of the invention, discharged in a predetermined direction.

A further object is to so improve the means employed for admitting air to, and for circulating air about the apparatus so as to secure the maximum cooling effect resulting from the absorption by the air of the atomized liquid, and as subsidiary to this latter object to provide against the accumulation in the apparatus of dust or other foreign material, such for example as the lint or "fly" commonly occurring in the air of textile establishments.

While the above objects may undoubtedly be attained in various ways, there is illustrated in the accompanying drawings one physical embodiment of the invention well exemplifying means suitable for the carrying into effect of the above objects.

Figure 1 is a central vertical section through a moistening device of portable form and constructed in accordance with the present invention;

Figure 2 is a horizontal section on the line 2—2 of Fig. 1;

Figure 3 is a fragmentary horizontal cross section on a line such as 3—3 of Fig. 1;

Figure 4 is a side elevation, partly in cen-

tral vertical section, of a modified form of humidifying device;

Figure 5 is a plan view of the device shown in Fig. 4;

5 Figure 6 is a fragmentary diagrammatic elevation illustrating a modified form of the upper portion of the apparatus shown in Fig. 4; and

10 Figure 7 is a diagrammatic side elevation to small scale illustrating the application to the device of Fig. 1 of means for controlling the direction of discharge of the moisture laden air.

Referring to Figs. 1, 2 and 3, a liquid container or receptacle is indicated at 1, this receptacle being of substantially circular, basin-like form. Upon the under surface of the receptacle 1 there may be provided lugs or bosses 2 serving as legs or supports for the same and such bosses may if desired, be furnished with resilient pads 3 secured thereto by screws 4 or in other desired manner, such pads serving to prevent marring of finished surfaces such as table tops or the like 20 on which the receptacle may be placed. Projecting from one side of the receptacle 1 is a boss 5, such boss being provided with a vertical passage or opening 6, which opening at its upper end is flared outwardly as indicated at 7. The opening 6 serves for the reception of the neck 8 of a bottle 9 supported in inverted position within the flared upper portion of said opening. Leading from the lower end of the opening 6 is a 35 lateral passage 10 which opens into the body of the receptacle.

The upstanding side walls of the receptacle 1 are so shaped as to provide, at a point intermediate the upper and lower edges of 40 the same, a lateral ledge or offset 11, and from the outer edges of said offset or ledge such walls are continued upwardly as indicated at 12 providing an inwardly inclined inner surface. Supported upon the upper 45 edge of the wall portion 12 is a spider device comprising an annular ring 13 which may be secured to the edge of the wall member 12 by means of screws 14, or in other desired manner. Extending inwardly from the ring 50 13 are a plurality of spaced arms 15 which are continued upwardly in a vertical direction as indicated at 16 and merge at their upper ends into a horizontal annular ring 18. The ring 18 is provided with the central 55 opening 19 and extending inwardly and upwardly from the edge of this opening are a plurality of legs 20 which serve to support a ring 21. This spider device as above described may consist of an integral stamping or casting, or may if desired, be built up of several independent parts suitably joined together.

Resting upon the ring 21 is an electric motor 22 to the terminals of which may be 60 attached the end of a flexible conductor cord

22^a whereby the motor may be placed in circuit with any suitable source of electrical energy. The motor 22 is provided with a vertically disposed shaft 23 to the lower end of which is secured a sleeve 24 detachably 70 fixed to the shaft by means of a set screw 25. The upper end of a shaft 26 is inserted within the sleeve 24 and may be fixed therein by means of a set screw 27. The shaft 26 extends downwardly into the receptacle 1 and 75 at its lower end is journaled in a bearing block 28 seated in a hollow boss 29 upstanding from the central portion of the bottom wall of the receptacle 1. At a point immediately below the end of the sleeve 24 a 80 hub 30 may be secured to the shaft to rotate therewith, such hub being provided with a series of fan blades 30^a. As herein illustrated such fan blades are of paddle form but it is contemplated that a fan of other 85 type might well be substituted if it were so desired. At a point within the receptacle and slightly above the plane of the ledge 11 there is fixed to the shaft 26 a hub 31 having a bore of substantially the same diameter as 90 the shaft and constituting the central supporting element of a substantially flat and horizontal disk, the outer part of which is formed of sheet material indicated at 32. This disk extends outwardly to a point such 95 that it slightly overlaps the ledge 11, the peripheral edge of such disk being spaced a short distance above the adjacent surface of said ledge. As a convenient mode of securing the outer part 32 of the disk to the hub 100 31, the latter may be furnished with an integral flange or rim 33 with which engages a downwardly directed flange 34 integral with the part 32. The members 33 and 34 may be secured together by rivets 105 or in any other desired and obvious manner, the central portion of the disk being closed or imperforate when mounted in operative position upon the shaft. The flange 34 is of truncated conical form extending downwardly to a point adjacent the upper surface of the bottom of the receptacle and having its open lower end encircling the boss 29 but being spaced therefrom as indicated at 35.

115 Interposed between the disk and the fan comprising the blades 30^a there is a cover member comprising the horizontal plate 36 provided with a central opening of a diameter closely approximating that of the shaft 120 26 and through which the shaft passes and having the dependent and substantially vertical flange 36^a. The plate 36 and flange 36^a are of such a diameter as to fit snugly between the inner surfaces of the arms 16 above 125 described and constitutes a partition which substantially prevents movement of air axially of the shaft. From the lower edges of the flange 36^a the cover is continued in an outwardly and downwardly inclined direc- 130

tion as indicated at 37 and from the lower edge of the part 37 the cover extends in a vertical direction, such vertical portion of the cover being slotted to provide a series of 5 vanes 38.

As indicated in Fig. 3 the vanes 38 are inclined to radii as R—R passing through the respective vanes, the angle of inclination of the vane to its respective radius herein 10 being shown as substantially 30° . The exact angle of inclination of the vanes, may however, be varied in accordance with the conditions under which the apparatus is to be used. In Fig. 3 the arrow X illustrates 15 the direction of rotation of the disk member 32 and it will be noted that the inclination of the vanes 38 is opposed thereto. While these vanes may be formed as independent elements secured to the member 37, it is preferred that they be provided by slitting the 20 material of the cover and bending the portion of such material lying between adjacent slits. The cover member as thus constituted is supported by the ledge 11, the 25 lower ends of the vanes 38 resting upon such ledge and the cover being properly centered by engagement of the flange 36^a with the arms 16 as aforesaid.

If desired there may be provided beneath 30 the cover above described a second fan comprising a hub 39 and blades 40, such hub being secured to the shaft 26 in any desired manner. While the device as thus described is particularly intended as a portable apparatus which may be moved freely from 35 place to place in a room or apartment, it is contemplated that it may also be used as a fixture or stationary appliance. In such case it may be found desirable to provide means 40 whereby air may be drawn from a source outside the room or compartment in which the device is situated. For this purpose there may be provided a casing or sleeve 41 surrounding the motor and having a flange 42 which rests upon the upper surface of the 45 ring 18 to which it may be secured by screws 43. This casing may be furnished with an opening for the passage of the conductor cord 22^a and if desired, may have a damper 50 44 of any desired character whereby to regulate the amount of air induced by the fan and actuatable by a handle 45 extending outside the casing. Such casing may also if desired, be furnished with a screen 45^a of 55 foraminous or reticulated material whereby to exclude dust or other foreign material from the apparatus.

A lateral opening 46 is provided in the sleeve 24, such opening communicating with 60 a longitudinal passage 47 in shaft 26. At the lower end of the shaft, radial openings 48 lead from the passage 47, the arrangement just described permitting oil to be fed into the interior of the bearing blade 28.

65 In the operation of the apparatus as thus

described, it being assumed that it is to be employed as a portable device, the receptacle 1 will be placed upon a table and the bottle 9 will be filled with water W as indicated in Fig. 1. The water from such bottle will 70

run out through the neck of the bottle until the water in the receptacle 1 has risen to the level of the neck of the bottle whereupon the water level in such receptacle will automatically be regulated by barometric pressure. Upon actuation of the motor, the disk member 32 is rapidly rotated and water in the receptacle 1 will be caused to climb up by centrifugal action (possibly assisted by capillary attraction) along the outer surface 75 of the flange 34 and will then move outward over the under surface of the disk. As the area of such surface increases rapidly from its inner to its outer portion it is evident that the film of water will be extremely 80 attenuated at the outer edge of the disk from which it will be thrown off with great force in the form of a thin film or of minute droplets. The provision of the automatic means for regulating the water level is of great importance in this connection as it is very desirable to prevent an excess amount of water 85 from reaching the under side of the disk in order to avoid the formation of unduly large drops. As these droplets are thrown off from the edge of the disk they impinge 90 with great violence against the opposed surfaces of the vanes and are broken up by the impact into the form of a substantially invisible mist which passes outwardly between the 95 vanes and upwardly through the annular space between the member 37 and the inner surface of the wall 12. The inclination of the latter surface is such as to oppose the upward flow of unatomized liquid and thus any 100 drops which may emerge from between the vanes are caught by such surface and turned back into the receptacle.

The fan comprising the blades 30^a serves 105 to cause an outward flow of air over the upper edges of the receptacle and this air flowing outwardly carries with it the atomized liquid which rises from the space between the wall 12 of the receptacle and the outer 110 surface of the flange 37 of the cover member, the minute particles of atomized liquid being quickly evaporated by contact with the air and converted into a true vapor. By reason of the rapid circulation of air through the apparatus and the absorption of water 115 thereby the temperature of the room or apartment in which the apparatus is installed may be very appreciably reduced. The fan comprising the blades 40, and which under some circumstances may be employed 120 within the cover member, serves to circulate the air within the space below cover 37 and thus prevents the accumulation of condensed moisture upon the under surface of the cover 125 from which large drops might fall on disk 130

33 and be expelled through the vanes 38 in particles of appreciable size and such as might cause damage to surrounding objects.

When this device is to be used as a fixed structure it is placed upon a suitable support and the casing 41 may be applied. The air will then be drawn in through said casing and through the screen 45^a if such be employed, and discharged into the room 10 through the openings between the legs 16.

In the arrangement shown in Figs. 4 and 5, the receptacle 50 is illustrated as furnished with an upstanding rim 51 and is provided upon its interior surface with a substantially horizontal annular ledge 52. In this case the receptacle 50 rests upon a bracket 51 which may be secured to a vertical support 52 of any suitable character. Resting upon the upper edge of the rim 51 20 is a spider comprising the vertical arm members 53 which merge into the horizontal portions 54. At their inner ends the parts 54 are united to a ring 55 and such parts may also be continued down at opposite sides 25 of said ring as indicated at 55^a, being united at their lower ends by means of an annular ring 55^b. Mounted upon the ring 55 is an electric motor 56 having a vertical shaft 57 on the lower end of which is secured a sleeve 30 58. Such sleeve may be connected to the shaft by means of a pin 59 or in other desired manner. The upper end of a shaft 60 is inserted within the sleeve 58 and is pinned thereto, such shaft projecting downwardly 35 into the receptacle 50 and being supported at its lower end in a bearing formed in a block 61 secured in a hollow boss 62 upstanding from the base of the receptacle at the center thereof. The sleeve 58 may if 40 desired, be provided with the lateral hole or opening 63 through which oil may be injected and leading from the interior of the sleeve is a passage 64 extending longitudinally of the shaft 60 and terminating at its 45 bottom in a plurality of radially extending openings whereby oil may be permitted to discharge into the bearing block 61.

Secured upon the lower part of the shaft 64 is a hub 65, an atomizing disk comprising 50 the substantially flat member 66. This disk member extends outwardly to a point above the ledge 52, the peripheral portion of such disk member 66 being spaced a slight distance above such ledge. Integral with the disk or 55 secured to it in any desired manner is a depending flange 67 of truncated conical form, such flange being open at its lower extremity and surrounding the boss 62 but being free from contact therewith. At a point 60 above the hub 65 there is secured to the shaft 60 a hub 68 carrying fan blades 69 of any desired form. Interposed between the fan and the motor is a cover device comprising the downwardly inclined sheet metal element 70 having at its central portion the

vertically arranged annular flange 72. The flange 72 engages the inner surface of the ring 55^b, hereinbefore referred to, and provides a large opening immediately above the center of the fan comprising the blade 70 69. The member 70 is continued downwardly in a vertical direction, such vertical portion being slotted to provide spaced vanes 71, these vanes being arranged substantially in the same manner as the vanes 75 38 previously described. The cover comprising the part 70 is supported upon the ledge 52 by engagement of the lower ends of the vanes 71 therewith, and is centered by engagement of the flange 72 with the ring 55^b. 80 Above the cover member 70 is provided a casing 73 having a depending flange 74 which fits loosely within the inner peripheral surface of the upstanding rim 51 of the receptacle. This casing is provided with a central opening which fits over the upstanding flange 72 of the cover 70. The casing 73 is provided with one or more openings 77, herein illustrated as two in number and arranged at diametrically opposite points 90 and leading into corresponding hoods 75, 76, which extend in a substantially tangential direction respectively. These hoods open in opposite directions as indicated at 78, see Fig. 5, so that air and water vapor passing 95 upwardly into the casing 73 is discharged in oppositely directed tangential streams from such hoods. As the casing 73 is freely rotatable, the direction of such streams may be varied at will. 100

Not only does the casing with its hoods serve as a means for determining the direction in which the air and atomized liquid vapor are discharged, but it also acts to retard and condense water particles of appreciable size and to cause them to flow back into the receptacle. While such directing hoods have been illustrated as applied to the form of device shown in Figs. 4 and 5, it is contemplated that the device of Fig. 1 110 might be furnished with a similar arrangement of parts if desired.

For supplying liquid to the container or receptacle 50 there is provided a pipe 79 extending up through a vertical opening in the bracket 51 and leading to any suitable source of fluid supply such as the reservoir 80, the discharge from which may be controlled by a float valve or other well known automatic device. The space between the 115 ring 55^b and the ring 55 is closed by semi-cylinders of gauze or other suitable screen material whereby air passing into the space beneath the cover 70 is freed from foreign matter such as lint or "fly" which is commonly found in the air of mills and other manufacturing establishments. 120

In accordance with the arrangement shown in Fig. 6, in place of the screen material 82, above referred to, the space immediately 130

below the motor 90 is entirely enclosed by means of a casing 92, and leading from said casing at the opposite sides thereof are a pair of pipes 93, 94 which merge into a common 5 conduit 95. Such conduit may lead to any desired point from which it is desirable to draw the air supply and thus the air passing through the humidifying apparatus may be drawn from a source outside the building where it is substantially free from dust 10 or foreign material.

In Fig. 7 a portable apparatus of the type of Fig. 1 is illustrated as comprising the receptacle 1^a, the reservoir 9^a, the spider or 15 support consisting of the legs 14^a, 15^a, the ring 18^a, and the legs 20^a supporting the motor 22^a. Surrounding the legs 15^a is a casing 100 having diametrically disposed, tangentially arranged discharge openings as 20 101. In this arrangement, the air discharged by the fan blades 3 (not shown), passes out between the legs 16^a, and after picking up the atomized liquid rising from the receptacle, is discharged in tangential, oppositely 25 directed streams through the openings 101. Preferably the casing 100 fits loosely over the legs 16^a, resting upon the members 14^a, and thus the direction of the discharge openings 101 may be varied at will. While it is 30 preferred to employ two discharge openings, a greater or lesser number might be provided if desired.

In the operation of the device illustrated in Fig. 4, the rotation of the blades 69 35 tends to cause an influx of air through the screen 82 such air passing downwardly through the opening in flange 72 and beneath the cover 70 and thence outwardly through the vanes 71 in a plane near the 40 upper ends of the latter. At the same time the rotation of the disk 66 acts by centrifugal force to draw water from the reservoir and to project it in the form of an attenuated film or of minute droplets from the 45 peripheral surface of the disk.

Such film impinges with great force against the vanes 71 and is thus reduced to a fine mist which passes out between the vanes and is caught up by the air current produced 50 by the fan blades 69. This air current, with its atomized liquid, passes into the casing 73 with a swirling or rotary motion and by reason of the tangential arrangement of the discharge hood, is ejected with considerable 55 force from the latter, being thus thoroughly mingled with the atmosphere of the room or apartment.

While water has been referred to throughout the above description as a suitable moistening agent, it is contemplated that under certain circumstances the water might serve as a medium for the distribution of disinfecting fluids or other substances with which it is desired to impregnate the air of the room or apartment. The structure thus pro-

vided is simple in form, compact and durable, easily installed and in the embodiment illustrated in Fig. 1 may be readily transported from one position to another in a room or apartment, thus permitting moisture to be discharged at that place where it is found to be most desirable, while by the use of the adjustable discharge hood, the direction of the current of moisture laden air may readily be determined.

While a specific embodiment of the invention has herein been disclosed it is to be understood that various changes and modifications in arrangements of parts as well as substitutions of equivalent parts for those herein disclosed may be made without departing from the spirit of the present invention.

What I claim is:

1. A portable humidifying apparatus 85 comprising a shallow basin constructed and arranged to be set upon a table or similar support, liquid atomizing means therein comprising a rotating disc, an air impelling fan, a fixed partition interposed between the disc and fan, a motor for actuating said atomizing means and fan supported upon said receptacle, and a flexible conductor cord whereby to connect said motor to a source of electric energy.

2. A humidifier comprising a shallow circular portable receptacle, a disc having a closed central portion rotatable therein about a vertical axis, automatically acting means portable with the receptacle for supplying liquid to said receptacle, a removable spider mounted upon said receptacle and providing a support for a motor, a motor mounted thereon, means for connecting said disc and motor whereby to rotate said disc, 100 and a centrifugal fan arranged within said spider and rotatable by said motor for expelling air radially from the casing.

3. A humidifier comprising a shallow receptacle having an upstanding rim, said rim being provided with an annular internal flange at a point intermediate its height, a disc member rotatable about a vertical axis within said receptacle, the plane of such disc member being slightly above that of 110 said flange, and a cover member above said disc and provided with portions freely engaging said flange whereby to support said cover member.

4. A humidifier comprising a liquid-receiving basin having a central upstanding boss provided with a vertical journal opening, a shaft rotatable within said journal opening, a disc member fast to said shaft and arranged to turn in a plane intermediate the 125 depth of the basin, and a cover member superposed upon said disc and having a central opening of a diameter slightly larger than that of the shaft through which the shaft passes, said cover member being pro- 130

- vided with portions engageable with said basin whereby to support said cover member in operative position.
5. A humidifier of the portable type comprising a circular basin, a bearing arranged centrally thereof and integral therewith, a shaft, a disc member secured to said shaft and rotatable within said receptacle, a flange depending from said disc and surrounding said bearing, a motor for driving said shaft, a fan interposed between said motor and disc, and a cover member supported within said receptacle and interposed between said disc and fan.
- 10 15. 6. A humidifying device comprising a liquid containing vessel, an atomizing disc, a shaft for supporting the same, a motor for driving the shaft, a fan mounted upon said shaft adjacent said disc, a cover interposed between said fan and motor, and a second fan mounted upon said shaft and intermediate said cover and motor.
- 20 25. 7. A portable humidifier of the class described comprising a shallow, liquid-holding receptacle of circular form, an imperforate substantially flat disc rotatable within said receptacle and of a diameter substantially smaller than that of the latter, a cover member arranged to lie in a plane above that of the disc, a fan provided with paddle-like blades arranged immediately above said cover, and means to actuate said disc and fan whereby liquid is ejected by said disc and is atomized by contact with elements of the cover and as the atomized liquid emerges from the upper edge of the receptacle it is laterally expelled by said fan.
- 30 35. 8. A portable humidifier comprising a substantially circular liquid receptacle, an imperforate disc member within said receptacle and rotatable about a vertical axis, a cover member arranged above said disc, said cover member constituting a partition to prevent substantial axial movement of air and being of a diameter greater than that of the disc, a series of vanes fixedly united to the cover member and depending from the edge of the same, and means for rotating said disc.
- 40 45. 9. A portable humidifying device of the class described comprising a receptacle for liquid, a circular imperforate and substantially flat disc rotatable about a vertical axis and arranged within said receptacle, a cover member constituting a horizontal partition overlying said disc and having a depending flange intersecting the plane of said disc, said flange comprising a series of spaced relatively fixed vanes arranged in non-radial planes, and means for rotating said disc in a direction opposite to the angle of inclination of said vanes.
- 50 55. 10. A portable humidifying device of the class described comprising a basin having an upstanding rim, a disc arranged for ro-
- tation within said basin in a substantially horizontal plane, a horizontal partition extending across said receptacle and constituting a cover therefor, said cover having a depending flange, the diameter of said flange being greater than that of the disc, said flange comprising a series of angularly disposed non-radial relatively fixed vanes, means for engagement by the ends of said vanes whereby to support said cover member in a plane above that of the disc, and means for rotating said disc in a direction such that moisture thrown therefrom by centrifugal action is diverted by contact with said vanes to move in a direction substantially opposite to the direction of rotation of the disc.
- 60 65. 11. A humidifying apparatus comprising a liquid containing receptacle, means for admitting liquid thereto, liquid atomizing means within said receptacle comprising a rotatable disc, a cover for said receptacle, a supporting structure mounted upon said receptacle, a fan arranged above the cover and having a motor driven shaft extending through an opening in said cover for actuating the disc, an air admission opening in said supporting structure, and means for screening air flowing to said opening.
- 70 75. 12. A portable humidifying apparatus comprising mechanical means for reducing liquid to a mist-like form, independent means for producing a current of air whereby to convey away such mist-like liquid after its formation, and adjustable means for determining the direction of discharge of the mist-laden air current.
- 80 85. 13. A portable humidifying apparatus comprising means for reducing liquid to the form of a mist, rotating means for producing a rotating body of air for conveying away such mist, and an outlet passage arranged tangentially to said rotating body of air whereby to determine the direction of discharge of the same.
- 90 95. 14. A humidifying apparatus comprising a water container and mechanical means associated therewith for atomizing water, means for producing an air current for conveying away such atomized water, and an angularly adjustable hood arranged above said container and supported thereby, said hood providing an air passage through which the moisture-laden air current is discharged.
- 100 105. 15. A humidifying apparatus comprising a circular receptacle for liquid, means for reducing such liquid to the form of mist, independent means for producing an air current, and a casing adjustably rotatable about the axis of said receptacle and having a tangentially directed outlet opening whereby optionally to determine the direction of discharge of said air current and mist.
- 110 115. 16. A humidifying apparatus comprising

a circular liquid container having means therein for atomizing liquid, independent means whereby air may be caused to circulate in proximity to the atomizing means for 5 conveying away the atomized liquid therefrom, and a casing into which the moisture-laden air is discharged, said casing being angularly adjustable about the axis of the container and having a tangentially directed 10 outlet passage.

17. A humidifying apparatus comprising a circular liquid container, means thereon for atomizing liquid and for circulating air in proximity of said atomizing means, and 15 a circular casing angularly adjustable about the axis of the receptacle and into which the circulating air is discharged, said casing having a pair of diametrically opposed tangential outlet passages.

18. A humidifier of portable type comprising a shallow circular receptacle having an atomizing disc turning therein in a plane spaced from its bottom, means for maintaining liquid in said receptacle at a constant 20

level below the disc, a cover for the receptacle enclosing the disc, a shaft to which the disc is fixed, a motor for driving the shaft, and a motor supporting spider mounted upon the rim of the receptacle and having means for centering the cover relatively to 25 the receptacle.

19. A portable humidifier comprising a shallow circular receptacle for liquid, said receptacle having a boss upstanding from its bottom adjacent to its center, a vertical 30 shaft resting upon a step bearing in said boss, said shaft having an axial bore opening at one end adjacent to the bearing and at the other at a point above the top of the receptacle, an atomizing disc fixed to the 35 shaft within the receptacle, a cover for the receptacle enclosing the disc, and a motor supported upon the receptacle and operatively connected with the shaft.

Signed by me at Pawtucket, R. I., this 6th 40 day of June, 1921.

BERTRAM M. MILLS.
